US00D861117S

(12) **United States Design Patent** (10) Patent No.: **US D861,117 S**
(45) Date of Patent: ** *Sep. 24, 2019

(54) **LASER DEVICE**

(71) Applicant: **Crimson Trace Corporation**,
Wilsonville, OR (US)

(72) Inventor: **William Johnston**, Wilsonville, OR
(US)

(73) Assignee: **CRIMSON TRACE
CORPORATION**, Wilsonville, OR
(US)

(*) Notice: This patent is subject to a terminal disclaimer.

(**) Term: **15 Years**

(21) Appl. No.: **29/623,634**

(22) Filed: **Oct. 26, 2017**

(51) LOC (12) Cl. **22-01**

(52) U.S. Cl.

(57)

CLAIM

The ornamental design for a laser device, as shown and described.

DESCRIPTION

FIG. 1 is a perspective view of a laser device, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dashed lines in the figure drawings depict unclaimed portion of the laser device only and form no part of the claimed design.

1 Claim, 7 Drawing Sheets
